Primary Examiner — George D Kirschbaum*Assistant Examiner* — Clese Moore, Jr.(57) **CLAIM**

The ornamental design for a grip enhancing tire attachment, as shown and described.

DESCRIPTION

FIG. 1 is a front view of a grip enhancing tire attachment showing my new design;

FIG. 2 is a rear view of the grip enhancing tire attachment; FIG. 3 is a top view of the grip enhancing tire attachment; FIG. 4 is a bottom view of the grip enhancing tire attachment;

FIG. 5 is a right side view of the grip enhancing tire attachment, a left side view being a mirror image thereof; FIG. 6 is a top front side perspective view of the grip enhancing tire attachment; and,

FIG. 7 is a front view of the grip enhancing tire attachment in use.

The broken lines shown in FIG. 7 illustrates environment that form no part of the claimed design.
